DESIGN FOR A MOVIE PROJECTOR CARRYING CASE

Jack Briskin, Chicago, Ill., assignor to Revere Camera Company, Chicago, Ill., a corporation of Delaware

Application October 20, 1947, Serial No. 142,029

Term of patent 14 years

(Cl. D61—1)

To all whom it may concern:

Be it known that I, Jack Briskin, a citizen of the United States, residing at Chicago, in the county of Cook and State of Illinois, have invented a new, original, and ornamental Design for a Movie Projector Carrying Case, of which the following is a specification, reference being had to the accompanying drawing, forming a part thereof, in which,

Fig. 1 is a side elevational view of a movie projector carrying case, showing my new design;

Fig. 2 is a view of one end thereof;

Fig. 3 is a view of the other end thereof;

Fig. 4 is a top view thereof;

Fig. 5 is a side elevational view of the opposite side to that shown in Fig. 1; and
Fig. 6 is a bottom view thereof.

I claim:

The ornamental design for a movie projector carrying case, as shown.

JACK BRISKIN.
